corporation of California

Application July 2, 1935, Serial No. 29,493

3 Claims. (Cl. 40—132)

My invention relates to signs of the type shown in my co-pending application Serial No. 741,917, filed August 29, 1934, and entitled "Illuminated sign". In such application there is provided a housing within which is a linear source of light, such as a gaseous discharge tube, which illuminates a plate having suitable indicia thereon.

It is an object of my invention to provide an improved sign.

Another object of my invention is to provide a sign in which a shield is established over the source of light and is constructed in such a way as to be indistinguishable from the background, especially when the sign is illuminated.

Another object of my invention is to provide a sign in which an inexpensive shield is provided for the source of light.

The foregoing and other objects are attained in the embodiment of the invention illustrated in the drawing, in which—

Fig. 1 is a front elevation of a sign constructed in accordance with my invention, as it appears when illuminated.

Fig. 2 is a cross-section the plane of which is indicated by the line 2—2 of Fig. 1.

Fig. 3 is a front elevation of a front plate for the sign of my invention, as it appears without illumination.

Fig. 4 is a cross-section on a very much enlarged scale of the front plate of Figs. 1 and 3, the plane of section being indicated by the line 4—4 of Fig. 1.

In its preferred form the sign of my invention includes a casing providing a background for a source of light such as a gaseous discharge tube situated within the casing, and a sign plate over the front of the casing to receive suitable indicia.

With the front plate is incorporated a shield, preferably composed of an almost infinite number of fine spots or dots of a coating such as paint, graduated in density from a maximum value substantially in registration with the source of light and gradually fading to a minimum value away therefrom.

The sign illustrated in the drawing as an example preferably comprises a casing 6 fabricated of metal or other suitable material and of any convenient shape. While in my copending application I have shown a casing which is substantially V-shaped in vertical cross-section, the present one exemplifies a variation and is approximately rectangular in section. It is provided on its forward periphery with an inturned flange 7 against which a front or sign plate 8 of

glass or comparable transparent material is situated, although a gasket 9 is preferably interposed therebetween. A closure ring 11 of flanged construction overlies the plate 8 and secures the assembly together.

Within the casing is situated a source of light 12, such as a linear, luminous tube 13, preferably of the gaseous discharge or neon type. The tube preferably extends transversely across the casing 6 in a straight line and is situated a slight distance behind the plate 8. Light emanates from the entire periphery of the tube and some of it passes directly through the transparent plate 8, while some of the light is first reflected from the interior of the casing 6 and then passes through the plate 8. The casing 6 is preferably provided with a light reflecting and diffusing coating, such as flat paint, for the purpose of returning light to and through the plate 8. On its inner surface, preferably, the plate 8 is treated to establish any suitable indicia 16, such as the word illustrated. This can be done by making a dark background or field, with the letters of a lighter shade or transparent, or, alternatively, the letters may be dark and their surroundings light or transparent.

Under any conditions, it is very desirable that the linear source of light 13 be in effect blended with its background, so that the sign as a whole will present to an observer in front of the plate 8 an appearance of a uniform intensity of illumination. Without some special means being provided to produce this desired result, the sign shows an exceedingly bright or light stripe where the tube 13 is situated, and darker spaces on either side thereof.

In accordance with my present invention, I preferably provide on the reverse or inner side of the plate 8, adjacent the situation or location of the tube 13, a treated area 17 or strip which is composed preferably of almost innumerable dots or particles of pigment, such as paint, adhering to the inner face of the plate 8 with a maximum density as at 18 where they are in substantial registration with the tube 13, and gradually decreasing in density as at 19 from the dense central area toward the edges of the stripe where they are farther away from the tube 13. The effect of this is to provide a graduated mask for the plate 8 immediately adjacent the tube 13, with more permeable portions of the mask overlying the more remote portions of the reflector 6, so that to an observer there is a uniform intensity of illumination of the entire sign.

Preferably, the stripe 17 is provided by utilizing a paint spray gun in such a way that a considerable quantity of pigment is applied adjacent the center of the strip 17, whereas increasingly sparse applications are made as the air gun is applied away from the center line of the tube. In an average schematic cross-section of the treated plate 8, as shown with some exaggeration in Fig. 4, there is disclosed a tapering thickness 10 of masking or shielding material 17 which in certain portions of the sign, as illustrated, is overlain by the pigment 16 which outlines or formulates the indicia.

I claim:

15 1. A sign comprising a casing, a gaseous discharge tube source of light in said casing, a light transmitting indicia plate on said casing overlying said source of light, and a pigment shield on said plate in registry with said linear source 20 of light and gradually varying in density from

a maximum adjacent the center thereof to a minimum away from the center thereof.

2. A sign comprising a casing, a gaseous discharge tube for illuminating the interior of said casing, a light transmitting indicia plate on 5 said casing overlying said tube, and a shield on said plate of maximum density in registration with said tube and of progressively lesser density away therefrom.

3. A sign comprising a light reflecting casing, 10 a linear gaseous discharge tube affording a source of light within said casing, a light transmitting indicia plate on said casing and overlying said tube, a light shield of gradually varying density 15 on said plate, the maximum density of said shield being in registry with said source of light, and means on said plate and in contact with said shield for providing indicia.
